UNITED STATES PATENT OFFICE.

JOSEF VOGEL, OF MUNICH, GERMANY.

CARBURETOR.

Application filed February 2, 1920, Serial No. 355,868, and in Germany November 18, 1918.

(GRANTED UNDER THE PROVISIONS OF THE ACT OF MARCH 3, 1921, 41 STAT. L., 1313.)

The invention relates to carburetors for combustion engines, and has for its object to make it possible to accurately regulate the fuel supply.

5 In order that my invention may be fully understood and more readily carried into practice, I have caused to be appended hereto two sheets of drawings illustrating three constructional examples thereof, 10 wherein:

Figures 1 and 2 are views of different structures in vertical section,

Figure 3 is a view in cross section on line A—A of Figure 2, and

15 Figure 4 is also a view in vertical section of a further modification.

In the constructional example shown in Figure 1, *a* is the carburetor casing having a main air passage *i*, and in which is arranged 20 a bridge *e* having a supply passage *n* for the fuel coming from the float chamber *d*. The bridge *e*, which is situated beneath the throttle valve *b*, contains a distributing tube *f*, which is pushed in from the side and is 25 prevented from rotating by means of a pin *p* and is pressed in a fluid tight manner against its seat *h* by a screw cap *g*. In the distributing tube *f* and in the bridge *e* are provided supply holes *r*, *s*, *t* arranged one 30 behind another in a vertical plane. In addition the carburetor casing *a* has an air inlet passage *l*, which opens into the passage *r*; the passage *r*, for throttling purposes is provided with a set screw *m* and serves for 35 idle running of the engine.

The supply holes *r*, *s*, *t* are so arranged in relation to the hole *k* of the throttle valve *b* that, on moving the same from idle running to full power, only the hole *r* is first 40 uncovered, whereby only a small amount of fuel can flow out. Then, on further rotation of the valve *b*, the hole *s* is uncovered for the purpose of increasing the supply of fuel and thereby obtaining a uniform 45 change from idle running to full power of the engine, until finally in the open position of the valve *b* the hole *t* becomes also uncovered, whereby the motor runs with full carburation. In this case the hole *r* 50 for idle running remains closed as shown in the position illustrated in Figure 1. The air tube *o* which may be of different sizes can be screwed into the carburetor casing *a* for the purpose of enabling the carburetor

to be employed for different sizes of engines. 55

The constructional example shown in Figures 2 and 3 differs from that shown in Figure 1 in that the fuel supply is distributed in greater quantity, more particularly for powerful engines. 60

The supply holes *s*, *t* are provided at their mouths which face the valve *b* with extensions or grooves *u* *v* of different sizes, which gradually pass into the curve of the carburetor casing *a*, see Figure 2. 65

After opening the hole *r* by means of the throttle valve *b*, the main air passage *i* of the carburetor casing, becomes open, whereby a part of the groove *u* is uncovered and the fuel comes out of the hole *s*. Further 70 rotation of the throttle valve *b* results in the main air passage becoming more and more open; and the same effect is produced on the groove *v*, until the hole *t* becomes uncovered. Hereupon, on fully opening the 75 throttle valve *b* the second supply hole *t* and its groove *v* are uncovered. The combustible mixture of air and fuel is proper mixture for every intermediate position of the throttle valve *b*. 80

In Figure 4 a constructional example is illustrated which is particularly suited for quick and thorough carburation of heavy fuels such as heavy benzol, heavy oil, and so forth. The usual priming cup is used in 85 starting.

For this purpose the distributing tube *f* is provided with annular grooves *w* or similar cavities at the mouths of the holes *r*, *s*, *t*, from which grooves further holes *x* lead 90 through the bridge *e* into the main passage *i*. The supply passage *n* for the fuel, in this case is also formed as a fuel mixture chamber because the air supply pipe *y* is provided, whereby a mixture of fuel with air 95 takes place when the engine is running. This mixture arrives through the distributing tube *f* into the annular grooves *w* and from these to the holes *r*, *s*, *t*. Simultaneously the engine draws in air through the holes *x* which also enters the annular grooves *w*. This air travelling through the annular grooves round the distributing tube *f* mixes with the mixture coming from the supply passage *n* and ensures a further thorough 100 division of the same, whereby the fuel is made more capable of combustion. 105

It is to be noted that the annular grooves

w may be combined with the construction shown in Fig. 2.

I claim:

- 5 1. A carburetor comprising a casing, a bridge piece extending across the casing and having a plurality of passages extending therethrough in the direction of the air flow, a fuel-distributing tube mounted in the bridge piece, intersecting said passages, having peripheral grooves and openings from its bore to said grooves, said grooves connecting the parts of said passages above and below said tube, and a throttle valve mounted in the casing and adapted to successively control said passages.
- 10 2. A carburetor comprising a casing, a

bridge extending across the casing and having a plurality of passages extending therethrough in the direction of air flow and terminating in arcuate tapered extensions; a 20 fuel-distributing tube mounted in the bridge piece, intersecting said passages, having peripheral grooves and openings from its bore to said grooves, said grooves connecting the parts of said passages above and below said tube, and a cylindrical throttle valve rotatably mounted in the casing and arranged to successively control the tapered extensions of said passages.

In testimony that I claim the foregoing as 25 my invention, I have signed my name.

JOSEF VOGEL.
